UNITED STATES PATENT OFFICE.

JOHN W. CARR, OF BRADDOCK, PENNSYLVANIA.

SAFETY-ENVELOP.

No. 927,112.

Specification of Letters Patent.

Patented July 6, 1909.

Application filed March 9, 1909. Serial No. 482,408.

To all whom it may concern:

Be it known that I, JOHN W. CARR, a citizen of the United States, residing at Brad-
dock, in the county of Allegheny and State of
Pennsylvania, have invented certain new and
useful Improvements in Safety-Envelops, of
which the following is a specification, refer-
ence being had to the accompanying draw-
ings.

10 This invention relates to improvements in
safety envelops of that class having specially
constructed sealing devices, whereby the
envelops cannot be opened without rendering
detection possible.

15 The object of the invention is to provide a
simple and practical safety envelop which
may be produced at a small cost and which
when sealed cannot be opened without so
mutilating it that the receiver will know that
20 the letter has been tampered with.

With the above and other objects in view,
the invention consists of the novel features of
construction and the combination and ar-
rangement of parts hereinafter fully de-
25 scribed and claimed, and illustrated in the
accompanying drawings, in which—

Figure 1 is a plan view of the blank from
which the improved envelop is made; Fig. 2
is a view of the envelop partially made up
30 and ready for use; Fig. 3 is a view of the
envelop closed and sealed; Fig. 4 is a longitudi-
nal section taken on the plane indicated by
the line 4—4 in Fig. 3; and Figs. 5 and 6 are
35 transverse sections taken, respectively, on
the planes indicated by the lines 5—5 in Fig.
2 and 6—6 in Fig. 3.

The improved safety envelop is formed
from a single blank shown in Fig. 1 and com-
prising a front body member 1 and a rear
40 body member 2 adapted to be folded over on
the member 1 along the dotted line 3. Said
members are of the same size and preferably
rectangular in shape, as shown. Upon the
upper and lower longitudinal edges of the
45 member 2 are formed large rectangular flaps
4, 5 each of which is approximately half the
size of the member 2 so that when they are
folded over upon the latter along the dotted
lines 6, said parts 2, 4, 5 will form a pocket or
50 compartment 7' for the reception of the con-
tents of the envelop. When the flaps 4, 5
are folded over, as shown in Fig. 2 of the
drawings, they are held in such position by a
transverse end flap formed at the free end of
55 the member 2 and adapted to be folded over
along the dotted line 8 and to be gummed to

the flaps 4, 5. The flap 7 has its inner face
covered with adhesive material 9 and adja-
cent its ends it is slit transversely a number
of times to provide separate tongues 11 60
which when gummed to the flaps 4, 5 will
effectively prevent them from being loosened
by means of a sharp instrument, by steam-
ing them, etc., without so mutilating said
parts as to render detection possible. Upon 65
the free end of the front body member 1 is a
triangular-shaped sealing flap 12 adapted to
be folded over on the dotted line 13 and to
be gummed to the outer face of the rear
body member 2. Said flap 12 has its sur- 70
rounding edges coated with an adhesive
material 14 so that it will be effectively se-
cured to the member 2. To more effectively
secure the member 2 in its folded position on
the member 1, the latter has its inner face 75
provided with a strip of adhesive material 15
arranged adjacent to the dotted line 13. It
will be seen that said adhesive material will
be engaged by the flap 7 and the tongues 11
of said flap 7 will be thereby more effectively 80
secured to render it more difficult to loosen
said tongues by steaming the envelop.
To further secure the member 2 in its folded
position on the member 1, adhesive material
16 is placed upon one end of the outer face of 85
the upper flap 4 so as to cause said flap to be
gummed to the inner face of the member 1.
On the bottom edge of the member 1 is a tri-
angular sealing flap 17 adapted to be folded
over along the dotted line 18 upon the outer 90
face of the member 2 and the flap 12, said
flap 17 having its free edges gummed, as
shown at 19. Upon the upper and outer
edge of the member 1 is a triangular-shaped
sealing flap 20 adapted to be folded over 95
along the dotted line 21 and having its free
edges provided with adhesive material 22 so
that it can be gummed to the flap 17 and the
exposed portions of the flap 12 and member
2, as will be understood upon reference to 100
Fig. 3 of the drawings.

In using the envelop, the letter or other
contents is placed in the pocket 7' or beneath
the flaps 4, 5, the adhesive material at points
15, 16 is moistened and the member 2 then
folded over upon the member 1. The end
flap 12 is then gummed to the member 2 and
the bottom and top flaps 17, 20 are then suc-
cessively gummed to said folded parts to pro-
duce the sealed envelop shown in Fig. 3. 105

From the foregoing it will be seen that it
will be impossible to reach the contents of

the envelop when the latter has been properly sealed, without rendering detection possible. To reach the contents of the envelop, it is necessary to open the flaps 20, 17, 5 12 and to then separate the members 1, 2. It will be practically impossible to loosen the flaps 20, 17, 12 without so disfiguring or mutilating the envelop as to indicate that the same has been tampered with, and it will 10 be impossible to separate the member 2 from the member 1 without rendering detection possible since the adhesive material 16 effectively holds the member 2 to the member 1 at one end of said members while the adhesive material 15 accomplishes the same 15 purpose at the other end of the envelop. The provision of the tongues 11 and their gummed connection with both the flaps 4, 5 and the member 1 renders it impossible to 20 separate the members 1, 2 without mutilating said tongues and thereby making it evident that the envelop has been tampered with.

Having thus described the invention what 25 is claimed is:

1. A safety envelop comprising front and rear body members to be folded upon each other, the rear body member having a pocket to receive the contents of the envelop and 30 formed by folded flaps gummed to each

other, one of said flaps being slit to provide tongues, means for gumming the slit or tongue portion of the last mentioned flap to the front body member and sealing flaps upon the front body member to be gummed 35 to the outer face of the rear body member.

2. A safety envelop comprising front and rear body members to be folded together, upper and lower flaps on the rear body member to be folded upon the same, a gummed 40 end flap on the rear body member having its ends slit to form tongues, said end flap being adapted to unite said upper and lower flaps to form a contents receiving pocket upon the rear body member, adhesive material upon 45 the inner face of the front body member to be engaged by said end flap, adhesive material upon the outer face of the upper flap on the rear body member to engage the inner face of the front body member and gummed 50 flaps upon the top, bottom and end of the front body member and adapted to be folded upon each other and the rear body member, substantially as described.

In testimony whereof I hereunto affix my 55 signature in the presence of two witnesses.

JOHN W. CARR.
